DISPLACEMENT PUMP

David T. James, Middletown, and Arthur J.
Rawson, Rocky Springs, Md.

Application December 31, 1948, Serial No. 68,708

5 Claims. (Cl. 103—149)

(Granted under the act of March 3, 1883, as
amended April 30, 1928; 370 O. G. 757)

1

This invention relates to pumps, particularly to an improved positive displacement pump in which an eccentric member compresses an elastic tube to expel the contents of the tube.

The invention described herein may be manufactured and used by or for the Government, for governmental purposes, without the payment to us of any royalty thereon.

Prior pumps of this type had several disadvantages. The compressing member set up severe strains and distortions in the tube member. Disintegration of the tube was hastened by frictional or abrasive action, with resultant excessive maintenance and replacement costs.

The primary object of the present invention is to improve the construction, assembly, and operation of a pump of the type described herein. Another object is to provide such a pump in which standard rubber tubing can be employed. A further object is to provide such a pump that is capable of delivering an exact measured quantity of fluid, as required by the automatic inoculating apparatus described in the co-pending application of John C. Wagner and David T. James, filed December 16, 1948, Serial Number 65,542.

Other equally important objects will more plainly appear from the detailed specification and drawings herein presented in exemplification but not in limitation of the present invention. Like reference characters represent like parts of a preferred embodiment of the present invention, shown in the accompanying drawings which illustrate diagrammatically in:

Figure 1; an isometric view of the assembled pump mechanism with portions shown broken away, for clarity.

Figure 2; an isometric view of the pump core showing the tube arrangement and the inlet and outlet path for the fluid.

Figure 3; a vertical longitudinal cross-sectional view taken on the plane 2, 2, 2, 2 of Figure 1.

Figure 4; a vertical transverse cross-sectional view taken on the plane 3, 3, 3, 3 of Figure 1.

As shown in Figure 2, elastic tubing 22 leads from container 21 and enters core 23 through inlet aperture 36, then out of slot 24 and around core 23 for more than one turn, and then into slot 25 and out of outlet aperture 26.

As shown in Figure 3, core 23 is joined to fixed shaft 15 by suitable attaching means such as bolt or screw 28.

As shown in Figure 4, outer ring 12 is rotated on shaft 15 by means of driving pinion 31 and driven gear 32 which is fixed to ring 12.

External ring or driven shell 12 contains an

2

eccentric pocket 30. Internal ring 11 is adjustably mounted in pocket 30. Internal ring 11 contains an eccentric pocket 40. Roller bearing 10 is mounted in pocket 40, and compressor ring 29 is mounted for free rotation in floating concentric contact with the internal circumference of bearing 10, and free floating eccentric contact with the outwardly disposed external wall of tube 22, and is arranged to progressively collapse tube 22 inwardly against core 23, when in operation, as shown in Figures 1 and 3.

The amount of eccentricity afforded by pocket 40 is controlled by the rotational adjustment of ring 11 in pocket 30. This adjustment is made by first loosening screw 14 and thus releasing lock nut 13. This permits the relative adjustment to be made by turning ring 11 by hand. Thereafter ring 11 is clamped into its new adjusted position by tightening screw 14 and thus pulling lock nut 13 back into its locking position in its housing formed by groove 16 in ring 11, and by groove 17 in ring 12, as shown in Figures 3 and 4.

This permits adjustment to suit varying thicknesses of tubing. It also permits adjustment to a concentric position so that the assembly of core 23 and tubing 22 in the pump 20 can thereby be greatly facilitated.

Within the limits of the range from concentricity to maximum eccentricity, it is apparent that an infinite number of adjustments may be made. This affords accurate adjustment for tubes of various internal diameters and thereby provides means for accurately metering the amount of fluid delivered by one or more, or by fractional, revolutions of pump 20. This arrangement is particularly valuable when used in conjunction with the revolution control mechanism described in co-pending application of David T. James, filed December 31, 1948, Serial Number 68,707, which matured into Patent No. 2,537,673 dated January 9, 1951.

In operation, power may be applied to drive pinion 31. This rotates driven gear 32, and external ring 12, around fixed shaft 15, and core 23 which is joined to shaft 15.

Internal ring 11 is locked to external ring 12 as explained herein, and rotates with roller bearing 10, ring 12 and gear 32, around core 23, in the direction shown by the arrows in Figure 1. As ring 29 is free to rotate within roller bearing 10, it applies practically frictionless pressure inwardly on tube 22, as there is no relative sliding or slipping movement between tube 22 and ring 29.

Any tendency to slide or slip is overcome by the action of roller bearing 10 on ring 29. It is im-

portant to note at this point that the inward pressure of ring 29 on tube 22 compresses tube 22, which also reduces internal friction and wear on tube 22, as compared to prior pumps that apply outward pressure which acts to stretch the tubing and thereby increases the rate of wear thereon.

From the foregoing it becomes apparent that standard rubber or other elastic tubing may be employed, because the stationary core 23 holds the tubing in place without anchoring along one or more elements of the tubing, as shown in prior U. S. Patent No. 2,414,355, to Boris Bogoslowsky, issued January 14, 1947. Anchoring of any type will inescapably cause longitudinal shear which critically increases wear.

The present invention permits normal collapsing only, which also removes another cause of wear in prior pumps.

It is also apparent that core 23 may readily be removed from, or inserted in, pump 20 by means of the attaching bolt or screw 28. This permits rapid changing of tubing 22 to tubing of a different internal diameter when it is desired to change the capacity of pump 20. With a predetermined internal diameter of tube 22 and a predetermined effective length of tube 22, the volume of fluid delivered per revolution of pump 20 is easily determined.

With the direction of rotation as indicated by the arrows in Figures 2 and 4, fluid may be pumped from container 21 through tube 22 at inlet aperture 36 and at outlet aperture 26 where the fluid is ejected at the delivery end 27 of tube 22, as shown in Figure 1. A reversal of rotation reverses the direction of flow just described.

While a preferred embodiment of the present invention has been illustrated in the foregoing specification, it is not intended to be limited thereto but it is contemplated that it includes all modifications and embodiments within the spirit and scope of the appended claims.

We claim:

1. A pump comprising: a cylindrical core removably fixed to a stationary shaft; a length of elastic tubing wrapping around the cylindrical surface of said core; inlet and outlet means for said tubing; a source of fluid in communication with said inlet means; an external driven ring mounted for rotation about said core; means for driving said driven ring; a first eccentrically disposed cylindrical pocket in said external ring; an internal ring mounted in said first pocket and attached to said external ring for rotation about said core; means for rotatively adjusting said internal ring in said first pocket; a second eccentrically disposed cylindrical pocket in said internal ring; a roller bearing mounted in said

second pocket and attached to said internal ring for rotation about said core; a freely rotatable compressor ring mounted for floating concentric contact with the internal circumference of said roller bearing and for floating eccentric contact with the outwardly disposed external wall of said length of tube; said core and said tube being positioned in cooperating relationship with said compressor ring whereby in operation said compressor ring will progressively collapse said length of tube inwardly against said core.

2. In combination in a pump of the class described: a fixed cylindrical core; a length of elastic tubing entirely encircling said core; and movable compressor means encircling said core and adapted to be moved eccentrically thereon for progressively collapsing said tubing inwardly against said core.

3. In combination in a pump of the class described: a fixed cylindrical core; a length of elastic tubing around said core; inlet and outlet means for said tubing; a source of fluid in communication with said inlet means; an external eccentric member and an internal eccentric member arranged for rotation about said core; a ring arranged for freely floating concentric contact with said internal member and for freely floating eccentric contact with said length of tubing, whereby said ring will progressively collapse said length of tubing inwardly against said core, in operation, and thereby expel said fluid through said outlet means.

4. The combination of claim 3 that includes: means for readily removing and replacing said core, whereby said tubing may be replaced with tubing of a different diameter; means for rotatively adjusting the position of said internal member with respect to the position of said external member, whereby said ring will be in floating eccentric contact with tubing of said different diameter.

5. The combination of claim 3 that includes: an annular friction reducing member positioned between said ring and said internal member.

DAVID T. JAMES.
ARTHUR J. RAWSON.
